his Attorney

UNITED STATES PATENT OFFICE.

EMILE KALISKI, OF MONROE, LOUISIANA.

SPRING-WINDING DEVICE.

1,283,791.

Specification of Letters Patent. Patented Nov. 5, 1918.

Application filed December 31, 1917. Serial No. 209,733.

To all whom it may concern:

Be it known that I, EMILE KALISKI, a citizen of the United States, and a resident of Monroe, in the parish of Ouachita and State of Louisiana, have invented new and useful Improvements in Spring-Winding Devices, of which the following is a specification.

This invention relates to spring winding device and is particularly adapted to be used in connection with phonographs as a means for automatically rewinding the spring thereof.

An important object of the invention is to provide in a device of the above mentioned character a means whereby energy may be stored within the spring motor of the phonograph upon the raising and lowering of the phonograph cover.

A further object of the invention is to provide in a device of the above mentioned character a means whereby the several actuating elements employed in the device as a whole may be retained in engagement one with the other during their respective operating periods.

A further object of the invention is to provide in a device of the above mentioned character a means whereby the various working elements employed in the device as a whole may be actuated with the least possible amount of noise and friction.

A further object is to provide a device of the above mentioned character which is simple in construction, strong, durable, inexpensive to manufacture, and reliable in operation.

Other objects and advantages of the invention will be apparent during the course of the following description.

In the accompanying drawings forming a part of this specification and in which like numerals are employed to designate like parts throughout the same,

Figure 1 is a side elevation of a phonograph showing the device embodying my invention attached thereto.

Fig. 2 is a fragmental vertical central sectional view of the same.

Fig. 3 is a detail view of the device, and, Fig. 4 is a fragmental detail view of a double pawl and ratchet mechanism.

In the drawings wherein for the purpose of illustration is shown a preferred form of my invention, the numeral 5 indicates a

phonograph cabinet provided with a cover 55 which is hingedly connected thereto in a conventional manner. Upon the winding shaft 7 of the spring motor, not shown, there is fixedly secured a ratchet wheel 8 carrying a plurality of cammed faced teeth as indicated by the numeral 9. A yoke indicated by the numeral 10 is loosely mounted upon the winding shaft 7 and is adapted to encircle the ratchet wheel 8 as clearly shown in Fig. 3, the end members 11 thereof being 65 spaced a suitable distance from the ratchet wheel 8 to permit the reception of a pair of arms indicated by the numerals 12 and 13 therebetween, the arms 12 and 13 being provided with a plurality of teeth 14 and 15 respectively, the teeth 14 being oppositely pitched with respect to the teeth indicated by the numeral 15. The arm 13 at its upper end is slightly curved as shown at 16 and is provided with an elongated shank 17 carrying at its upper end an engaging head 18 through which a bolt or pin 19 is adapted to be passed in order to secure the same to the cover 6 as clearly shown in Figs. 2 and 3.

At the jointure of the shank 17 and the 80 curved portion 16 of the arm 13 there is pivotally connected a second arm 12 by means of a bolt or rivet 20 passed through a pair of flanges 21 and the end of the arm 12 retained therebetween, said flanges being 85 carried by a shank 17 as shown.

In order to retain the teeth 14 and 15 of the arms 12 and 13 respectively, normally in engagement with the teeth 9 carried by the ratchet wheel 8 there is provided a pair of 90 compressible springs 22, one end of each spring being retained within the recess 23 carried by the end members 11, while the other ends of the springs are adapted to engage the arms 12 and 13 as shown.

In use the operation of the device is as follows:

When the cover 6 is raised to the dotted line position shown in Fig. 1 the teeth 15 carried by the arm 13 engage the teeth 9 100 carried by the ratchet wheel 8 whereupon the same is rotated in a clockwise direction thereby storing energy within the spring of the spring motor, not shown. When the cover 6 is moved to the full line position 105 shown in Fig. 1 the teeth 14 carried by the arm 12 engage the teeth 9 carried by the ratchet wheel 8 thereby imparting a clock-

wise rotary motion to the ratchet wheel 8. It will be understood that when the ratchet wheel 8 is being rotated through the instrumentality of the teeth 15 that the teeth 9 carried by the ratchet wheel 8 will move successively over the teeth 14 carried by the arm 12 and that the teeth 9 will move successively over the teeth 15 when the teeth 14 engage the teeth 9 to impart rotary motion to the ratchet wheel 8 in a clockwise direction. It will be further understood that due to the change of position of the arms 12 and 13 with respect to the shaft 7 that the yoke 10 will be free to oscillate about the shaft 7 to accommodate this change of position.

It is to be further understood that the form of my invention, herewith shown and described is to be taken as a preferred example of the same; and that various changes 20 in the shape, size, and arrangement of parts may be resorted to without departing from the spirit of the invention or the scope of the subjoined claim.

Having thus described my invention, what 25 I claim as new and desire to secure and pro-

tect by Letters Patent in the United States, is:

In combination with a phonograph provided with a cover hingedly connected thereto and having a winding shaft of means for imparting rotary motion in a clockwise direction to said winding shaft upon the raising and lowering of said cover, said means comprising an arm provided with a plurality of teeth, said arm being pivotally connected 35 to said cover; a second arm pivotally connected to the first mentioned arm and provided with a plurality of teeth having a pitch opposite to that of the teeth carried by the first mentioned arm; a ratchet wheel 40 provided with a plurality of teeth secured to said winding shaft; a yoke loosely mounted upon said winding shaft and encircling both of said arms and said ratchet wheel; a pair of springs carried by said yoke and having 45 engagement with said arms, said springs serving as a means for normally retaining said arms in engagement with said ratchet wheel.

EMILE KALISKI.
